US00D464063S

(12) **United States Design Patent** (10) Patent No.: **US D464,063 S**
Thomas, Jr. et al. (45) Date of Patent: ** Oct. 8, 2002

(54) **COMPRESSOR**

(75) Inventors: **Delbert L. Thomas, Jr.**, Watervaliet, MI (US); **Lorraine Joan Westlake**, Eau Claire, MI (US)

(73) Assignee: **Gast Manufacturing, Inc.**, Benton Harbor, MI (US)

(**) Term: **14 Years**

(21) Appl. No.: **29/141,677**

(22) Filed: **May 10, 2001**

(57) **CLAIM**

The ornamental design for a compressor, as shown and described.

DESCRIPTION

FIG. 1 is a perspective view of the compressor of our invention.

FIG. 2 is an end elevational view of the compressor of FIG. 1 taken from the left end of FIG. 1.

FIG. 3 is a side elevational view of the compressor of FIG. 1. The opposite side view is substantially identical.

FIG. 4 is a top plan view of the compressor of FIG. 1.

FIG. 5 is a bottom plan view of the compressor of FIG. 1.

FIG. 6 is an end elevational view of the compressor of FIG. 1 taken from the right end of FIG. 1.

FIG. 7 is a perspective view of another embodiment of the compressor of our invention.

FIG. 8 is an elevational view of the compressor of FIG. 7 taken from the left end of FIG. 7.

FIG. 9 is a side elevational view of the compressor of FIG. 7. The opposite view is substantially identical.

FIG. 10 is a top plan view of the compressor of FIG. 7.

FIG. 11 is a bottom plan view of the compressor of FIG. 7; and,

FIG. 12 is an end elevational view of the compressor of FIG. 7 taken from the right end of FIG. 7.
